UNITED STATES PATENT OFFICE

EARL D. WOOD, OF IRVINGTON, NEW JERSEY.

ROPE-FASTENER.

1,072,556.

Specification of Letters Patent.

Patented Sept. 9, 1913.

Application filed August 5, 1912. Serial No. 713,413.

To all whom it may concern:

Be it known that I, EARL D. Wood, a citizen of the United States, residing at Irvington, in the county of Essex, State of New Jersey, have invented certain new and useful Improvements in Rope-Fasteners; and I do hereby declare the following to be a full, clear, and exact description of the invention, such as will enable others skilled in the art to which it appertains to make and use the same.

This invention relates to rope fasteners and has for an object to provide a device of this character that may be formed from a single blank of material and will be so constructed that the rope may be easily and quickly taken up or lengthened from time to time.

With the above object in view the invention consists of certain novel details of construction and combination of parts herein-after fully described and claimed, it being understood that various modifications may be made in the minor details of construction within the scope of the appended claim.

In the accompanying drawing forming part of this specification:—Figure 1 is a front elevation of the device in applied position. Fig. 2 is a plan view of the parts shown in Fig. 1. Fig. 3 is a longitudinal sectional view through the device. Fig. 4 is a detail perspective view of the device.

Referring now to the drawing in which like characters of reference designate similar parts, the device is formed preferably from a single blank of sheet metal 10 one end portion of which is stamped out to form a ring 11 to which the looped end 12 of a hammock cord 13 or other supporting cord is applied. The blank is provided centrally with a substantially U-shaped slot 14, and the material therewithin is struck outwardly and forwardly to provide a reversely curved spur 15, the free end of which is in alinement with and confronts the bill of the hook 11. The blank is formed with a substantially U-shaped recess 16 in rear of the integral end of the spur 15, the

recess opening through one longitudinal edge of the blank.

In applying the cord 17, the terminal of the cord is formed with a loop 18, and the loop passed over and engaged with the spur 15, the main length 19 of the cord being then engaged through the recess 16 and serving to clamp the terminal portion 20 of the cord against the blank, as shown in Fig. 1. By simply loosening the loop, and pulling on the terminal or shoving forwardly on the terminal, the cord 17 may be shortened or lengthened easily and quickly. It is to be noted that by the reversed curving of this spur 15 the cord is gradually jammed when stress is exerted thereon and the engagement is more effective in proportion to the stress exerted because the cord is pulled tighter into the narrower part of the space between the spur and the body of the device.

What is claimed, is:—

A rope fastener comprising a single blank 70 of metal, a cord secured at one end to said blank, a transverse slot formed in the opposite end of said blank to receive the free end of said cord, and an integral longitudinal tongue struck from said blank near the 75 inner end of said slot and having the free end turned away from said slot, said tongue being offset from said blank in a reverse curve having its lower portion concave above and convex below to provide a jamming portion of gradually decreasing taper, the free 80 end of said tongue being parallel with said blank, the free end of said cord being adapted to be passed from said slot around said offset root of the tongue thence directed 85 back and passed underneath that portion of the cord extending between said slot and said root with a resultant clamping between said portion and said blank when the cord is drawn taut about an article to be bound. 90

In testimony whereof, I affix my signature, in presence of two witnesses.

EARL D. WOOD.
